(57) **CLAIM**

The ornamental design for a tether pole game, as shown and described.

DESCRIPTION

FIG. 1 is a perspective view of a tether pole game, showing a first embodiment of my new design;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1; and,

FIG. 7 is a bottom plan view of FIG. 1.

The broken lines in the drawings depict portions of the tether pole game that form no part of the claim.

1 Claim, 4 Drawing Sheets
